MANUAL FEEDING AND TRIPPING MECHANISM FOR A POWER DRIVEN POSTAL MACHINE

John Q. Finfrock, Westwood, Calif., assignor to
National Postal Meter Company, Los Angeles,
Calif., a corporation of California

Application August 24, 1934, Serial No. 741,235

14 Claims. (Cl. 101—287)

This invention relates to a manual feeding and tripping mechanism for an automatic, power driven postal machine.

The feeding and tripping mechanism of this invention may be advantageously adapted to the postal machine illustrated and described in my copending application for United States Letters Patent Serial No. 723,094, filed April 30, 1934.

The machine of my copending application is especially adapted for use in the handling of speed mail, that is mail matter requiring but one, or at most two, postage stamps to be printed thereon. In treating speed mail which requires two stamps, the mail may be run through once after the machine has been set so that the date circle will not be printed thereon and after the first run this mail matter may be run for a second time but before starting the second run the machine will be adjusted so as to print the date circle and the tripping mechanism set to insure the printing of the second stamp next to instead of on top of the first impression. The operation of the machine for operating upon single and double run mail matter is fully described in the stated application. This machine is also adapted to print a plurality of postage stamps upon, what is called, over-weight mail matter and for this use the machine must be differently arranged as, for example, the envelope feeding conveyor truck should be removed, which act will render the envelope feeding conveyor inoperative and will release the hand tripping lever for use. The over-weight mail matter will not be placed in the feeding magazine but instead will be manually fed piece by piece to the postage printing meter or means and manually moved after the printing of each stamp until the allotted number of stamps have been printed thereon.

It is one of the principal objects of this invention to provide the postal machine of my copending application with a feeding and tripping mechanism manually operable for advancing the conveyor a predetermined distance with each actuation thereof and operable at substantially the completion of the conveyor advancing stroke to trip the driving mechanism into operation for driving the printing means through one full printing cycle. By the use of the feeding and tripping mechanism, the over-weight mail matter may be easily and quickly treated in the machine.

A further object is to provide a clutch means which may be manually operable for advancing the conveyor a predetermined distance with each actuation thereof and arranged when in its retracted position to be disconnected from the conveyor so as not to interfere with the operation thereof while it is being power driven.

A further object is to provide a limit means for governing the operating stroke of the clutch and

in this way predetermining the distance the conveyor will be advanced for each actuation of the clutch and to thereby correctly space each stamp printed upon the mail matter carried by the conveyor.

A further object is to provide a brake means which will act just as the clutch means arrives at the end of its conveyor advancing stroke to prevent the conveyor from over-traveling.

A further object is to provide a tripping means which will be actuated by the manually operable conveyor advancing means when this means approaches the end of its conveyor advancing stroke for placing the driving mechanism of the machine in driving engagement with the printing means.

A further object is to provide a control means operable for rendering the manually operable tripping mechanism inoperative to place the printing means into operation as long as the machine is arranged for automatic operation and further operable for disrupting the power driving connection to the conveyor and for simultaneously releasing the hand tripping mechanism.

Other objects and advantages of the invention will become apparent as the nature of the same is more fully understood from the following description and accompanying drawings, wherein is set forth what is now considered to be a preferred embodiment. It should be understood, however, that this particular embodiment of the invention is chosen principally for the purpose of exemplification and that variations therefrom in details of construction or arrangement of the parts may accordingly be effected and yet remain within the spirit and scope of the invention as the same is set forth in the appended claims.

In the drawings:

Figure 1 illustrates a top plan view of a postage printing machine of the type disclosed in my copending application, in which the manual feeding and tripping means of this invention has been incorporated. A portion of the enclosing casing has been broken away to more clearly illustrate the control mechanism of the machine.

Figure 2 illustrates a right hand side view of Fig. 1 partially in section to more clearly show the tripping mechanism which places the printing means in operation.

Figure 3 illustrates a fragmental sectional view of a portion of the means for rendering the manually operable tripping means inoperative.

Figure 4 illustrates a sectional view taken substantially in the plane of line 4—4 of Fig. 1.

Figure 5 illustrates a front elevational view of Fig. 1 showing the machine adjusted for manually feeding and tripping the machine when treating over-weight mail.

Figure 6 illustrates an enlarged fragmental sectional view of the manual feeding and tripping means in its retracted position.

Figure 7 illustrates a view similar to Fig. 6 but showing the feeding means at the end of its conveyor advancing stroke and having already actuated the tripping and brake means; and

5 Figure 8 illustrates a sectional view taken substantially in the plane of line 8—8 of Fig. 6.

The manually operable feeding and tripping means, forming the subject matter of this invention, may be incorporated in the postage 10 printing machine of my copending application. The machine of my copending application needs to be changed but little in order to adapt the invention thereto. Before pointing out these 15 changes and describing the invention in detail, it is believed that a brief description of the machine will aid in acquiring a better understanding of these changes and of the invention.

As a full and detailed description of the postal 20 machine may be found in my copending application, it is, therefore, deemed needless to repeat that description herein other than to briefly point out the principal elements of the machine and to describe in detail those elements and parts which directly relate to or are affected 25 by the incorporation of the invention therein.

The postal machine as illustrated in Figures 1 to 5 inclusive may include a power plant 10 to which a postage printing meter or means 11 may be detachably mounted. Mail matter 12 may be 30 placed in a hopper or magazine 13 from which it will be withdrawn one piece at a time by the conveyor means 14. The mail matter carried by the conveyor may be first passed over an envelope flap opening and moistening device 15 35 and then delivered to the postage printing means and after the stamp has been printed thereon it is ejected from the machine. At this time, it might be well to point out that the moistening device has been somewhat changed from its form 40 as shown in my copending application to that of my copending application Serial No. 735,578, filed July 17, 1934, entitled Envelope flap opening and moistening device.

The power plant is provided with a driving 45 mechanism 16 having an electric motor (not shown) for its prime mover and normally connected to the conveyor by a clutch means 17 and connectible with the printing means through a one cycle clutch 18 whereby when the printer 50 clutch is tripped into operation it will act to drive the printer through one full printing cycle and then automatically disengage to stop the printer. The one cycle clutch is provided with a cam 19 which acts through the cam lever 20 55 during its initial rotation to actuate the conveyor clutch control means 21 to disconnect the driving mechanism from the conveyor and to re-establish this driving connection when the cam arrives at the end of its operating cycle. Thus, 60 while the printer is in driving connection with the driving mechanism, the conveyor is automatically disconnected therefrom.

In Figures 1 and 4 the machine is shown in 65 condition to handle speed mail, while in Figure 5 it is shown as arranged to handle over-weight mail. The change necessary to adjust the machine to handle over-weight mail is made very easily and simply by removing the conveyor truck 22 (Figs. 1 and 4) and by rendering the envelope tripping lever 23 inoperative by depressing this lever below the line of travel of the envelopes carried by the conveyor by means of the friction lever 24. It is this tripping lever 70 75 which is engaged by each envelope as it moves

into printing position and is actuated thereby to place the printer into operation and to thereby stop the conveyor until the printing operation has been completed, whereupon the printer is automatically disconnected while the conveyor is again placed into operation to eject the treated envelope and advance the next succeeding one into printing position. As the over-weight mail matter is placed in printing position by hand, it is necessary to remove the conveyor truck to 10 make hand feeding of the mail matter easier and quicker and to maintain the tripping lever depressed or otherwise inoperative so that each piece of mail matter placed in printing position will not engage and swing this lever to trip the 15 printer driving clutch into operation and thus prematurely bring about the printing operation. It has been found to be of considerable advantage to retain that portion of the truck which lies directly in front of the printer as it acts to hold 20 the mail matter in printing position and also, of possibly even more importance, weights the piece of mail matter under treatment down onto the conveyor and thus insures an accurate advancement of the envelope each time the conveyor is 25 advanced by means later to be described. Thus, the truck of my first mentioned application has been changed, which change includes dividing 30 the truck into two separate elements. The first or removable truck 25 is shown in position on the machine in Figures 1 and 4 and would be so mounted when the machine is set to handle speed mail but for over-weight mail it should be removed. To remove truck 25 it is necessary to lift only the spring weighted handle 26, which frees 35 the truck for removal. It will be understood that when handle 26 is raised, through suitable locking means 27 (Figure 4), it will be retained in its raised position and due to its interconnection with the conveyor clutch control means will act 40 to hold the conveyor clutch disconnected from the driving mechanism in the manner fully set forth in my first mentioned application. Thus, it will be appreciated that as long as truck 25 45 is removed from the machine, the conveyor will be maintained disconnected from the driving mechanism.

The rear portion 28 of the truck is now pivotally mounted upon a suitable spindle 29 projecting from the outer end of bracket 30, which may be 50 suitably fastened upon the front wall of the power plant. The rear truck 28 may be provided with three rubber tired wheels 31, all in line, and arranged to ride upon the upper surface of the conveyor belt 32. The rear end of truck 28 55 may be extended to form a handle 33 by which it may be swung around its spindle 29 and thereby lifted sufficiently for the insertion of mail matter into printing position, whereupon the truck may be released to hold the piece of mail in position 60 and onto the conveyor belt.

As each piece of the over-weight mail matter 65 will require a plurality of stamps printed thereon, it must be advanced between each printing operation to place the stamps in side by side relation. This, of course, may be done by hand but by hand feeding the envelopes the operation is slowed down and the stamps may not be accurately spaced, thus giving the treated envelope 70 an untidy appearance. Means are, therefore, provided which may be manually actuated for advancing the conveyor belt a predetermined distance and thereby carrying the envelope forwardly a correct distance for each stamp printed. 75

Manually operable feeding means

The manually operable feeding means may be operatively associated with the conveyor belt pulley 34 (Figs. 5, 6 7 and 8), and may include providing this pulley with a ratchet wheel 35 securely fastened thereto as by rivet means 36. An oscillatory plate 37 may be journaled upon the annular flange 38 of the conveyor belt pulley journal pin 39, which may be fastened to the inner face of the power plant outer wall 40 as by the shouldered machine screw 41. This oscillatory plate may be operatively connectible with the ratchet wheel by providing the plate with a pair of diametrically opposed pawls 42 and the finger of each of these pawls may be yieldingly urged into engagement with the teeth of the ratchet wheel by spring means 43. A hand piece 44 of convenient shape may be journaled upon the shank of screw 41 and operatively connected to the oscillatory plate by means of a horizontally projecting pin 45 which extends through an arcuate slot 46 formed in wall 40 and through a suitable bore formed in the plate. The arcuate slot 46 acts as a limit means for limiting the oscillatory motion which may be imparted to the plate for each stroke of the hand piece and thus controls the distance through which the conveyor belt may be advanced for each actuation of the hand piece. A torsional spring 47 may act between wall 40 and the hand piece to yieldingly retain this piece in its retracted position as shown in Figures 5, 6 and 8. When the hand piece is turned to its retracted position, the tail portion 48 of each of the pawls will ride under their respective retracting pins 49 (Fig. 6), which will act to lift the fingers of the respective pawls clear of the teeth of the ratchet wheel. Pins 49 may be fastened to and project horizontally from the rear face of the power plant wall 40. The advantage derived from lifting the pawls clear of the ratchet wheels is obtained principally when the conveyor is being power driven whereby the ratchet wheel may rotate freely without causing the pawls to ride in and out of its many teeth during this rotation and thus eliminating not only the disturbing noise which would be caused thereby but also unnecessary wear to these parts. The pawls will be released from their respective retracting pins during the initial rotation of the oscillatory plate whereupon the finger of each pawl will engage one of the ratchet teeth which are so related thereto as to form a driving engagement therewith whereby the ratchet wheel will be turned and thus, through the associated pulley, the conveyor will be advanced until pin 45 will have reached the other end of the limit slot 46. Upon completion of the advancing stroke of the conveyor, the parts will be returned to their retracted position under the influence of the torsional spring 41.

Manually operable tripping mechanism for the printing means

It is desirable to arrange the conveyor advancing means whereby at substantially the end of the conveyor advancing stroke this means will act to place the printing means in driving connection with the power plant driving mechanism. For this purpose the oscillatory plate 37 may have a portion thereof cut away, as at 50, which portion may have a cam surface 51 arranged to engage and swing the free end of the tripping arm 52 from its inactive position as

shown in Figure 6 to its active position as shown in Figure 7. The tripping arm is fastened at its opposite end to shaft 53 which corresponds to shaft 226 of my first mentioned application and, as the action of this shaft in tripping the printer clutch into action to establish a driving connection between the power plant driving mechanism and the printer is fully described therein, a repetition of this description is unnecessary. It is sufficient to say that the turning motion 10 imparted to this shaft during the swinging action of the tripping arm 52 from its position as shown in Figure 6 to that of Figure 7 will act through a suitable mechanism to place the printer driving clutch 18 into operation. 15

Due to this arrangement, the conveyor advancing means will function during its active stroke to swing the oscillatory plate until its cam surface 51 will engage and rock the tripping arm, and finally at substantially the end of the 20 stroke the tripping arm will have been rocked sufficiently to trip the printer clutch into operation.

Conveyor brake

25

In order to prevent the conveyor from overtraveling should the hand piece 44 be sharply turned, a brake means is provided which will be brought into action at substantially the end of the conveyor advancing stroke. In this embodiment, the conveyor brake means may be associated with the tripping arm 52, however, it may be differently arranged if desired. In Figures 6, 7 and 8, the brake shoe 54 may be appropriately fastened to the offset bracket 55 of the tripping 30 arm, as by rivet means 56. The brake shoe will directly underlie the lower run of the conveyor belt 32 and, as it is formed of metal having considerable resiliency, it will be brought into braking engagement with the conveyor belt when the trip 40 arm has been swung to its active position, as is clearly shown in Figure 7, without interfering with the action of the tripping lever or the conveyor advancing means. The brake will be automatically returned to its inactive position upon 45 the return of the tripping arm, as may be observed from Figure 6. This brake mechanism insures that the conveyor will not overtravel even though the hand piece be turned relatively quickly and thus the stamps printed upon a piece of mail 50 matter will all be equally spaced.

Locking means for the manually operable tripping means

The same control means 57 may be utilized in 55 this machine as in my first mentioned application for locking the hand tripping means against action during the time the machine is set for treating speed mail, for it would be inadvisable to leave the hand tripping means free to throw the 60 printer into action at any time while the machine is set for automatic operation as the printer might be placed into operation by its action before the conveyor would have had sufficient time to carry the piece of mail matter into printing 65 position, thus wasting the value of the stamp, or at best causing the stamp to be inaccurately placed thereon.

This control means, like in my stated application, is operatively associated with the spring 70 weighted handle 26 whereby it will be automatically actuated to release the hand tripping means when this lever is locked in its raised position for the removal of the forward portion of the conveyor truck and also while in this position 75

the handle will act to automatically disconnect the conveyor driving clutch. When handle 26 is lowered to position the forward truck in place on the conveyor, it will actuate the control means to lock the hand tripping mechanism and to release the conveyor clutch. In this way the machine is safe guarded against hand tripping the printer into use when the machine is set for acting upon speed mail and likewise, due to 10 retracting the tripping lever 23 by means of the friction lever, the printer cannot be placed into operation by means other than the hand tripping mechanism when the machine is adjusted to treat over-weight mail matter.

15 Operation

As the features of this invention are brought in to play only when the machine is adjusted to handle over-weight mail, the operation of the 20 machine for this purpose will be described.

The operative will usually assort all over-weight mail matter into one pile and pencil on each piece in small figures the value of postage required thereon. This done, the machine will be adjusted for treating this matter in the manner described. Thereupon, the operative will lift the rear truck 28 by means of handle 33 and place the first piece of over-weight mail matter in the machine so that the forward edge thereof will be positioned adjacent the inner edge of stamp 58 engraved upon the front face of the meter. Next, the date circle printing die will be shifted to its off position by shifting the date circle control knob 59 opposite the word "Off" engraved upon the printer casing, if a number of stamps are to be printed before requiring the printing of the date circle. If, for example, this particular piece of mail matter required six cents worth of postage, as penciled thereon, it would require three 35 two cent stamps to be printed thereon as the denomination of postage which may be printed by the meter illustrated is for two cents only. We will assume that meters of other denominations are not available.

45 The machine is now ready to print the first stamp, whereupon the operative by turning the hand piece 44 will actuate the conveyor to advance the envelope into printing position and as it reaches this position the printing means will be connected with the driving mechanism, further movement of the envelope will be stopped, during the printing operation. With the completion of the first printing operation, the operative may, by means of the hand piece, again advance the envelope and when it has been advanced a predetermined distance, the printer will again be placed into operation to print the second stamp. Before printing the third stamp, the operative will shift the date circle knob 59 until it is opposite the word "On" and will then actuate the hand piece for the third time, again advancing the envelope a predetermined distance before placing the printer into action, and during this printing cycle the machine will print the date circle along 55 with the stamp. The envelope will now have three 2 cent stamps printed thereon, as well as one impression of the date circle, and may be removed from the machine and the next envelope placed therein for treatment.

70 It will be understood that any number of stamps may be printed upon the mail matter for which there is room and, that after the piece of mail matter has been placed in the machine, it will not require further attention as it will be nicely held onto the conveyor by the rear truck

and will be accurately advanced during the actuation of the hand piece.

A machine incorporating the features of this invention will handle over-weight mail matter easily, quickly and accurately. 5

While I have illustrated the preferred form of my invention, it is to be understood that the foregoing description is for illustrative purposes only and I do not desire to be limited to any of the details shown or described, except as defined in the 10 appended claims.

I claim:

1. In a postage printing machine, postage printing means, driving means operable for driving the printing means through a single operating cycle each time said driving means is placed into operation, conveyor means for advancing mail matter through the printing means, means for manually advancing the conveyor, and means for placing the printer driving means into operation with each actuation of the conveyor actuating means. 15

2. In a postal printing machine, postage printing means, driving means operable for driving the printing means through a single operating cycle 25 each time said driving means is placed into operation, conveyor means for advancing mail matter through the printing means, means for manually advancing the conveyor a predetermined distance with each actuation thereof, and 30 means for placing the printer driving means into operation with each actuation of the conveyor actuating means.

3. In a postage printing machine, postage printing means, driving means operable for driving the printing means through a single operating 35 cycle each time said driving means is placed into operation, conveyor means for advancing mail matter through the printing means, conveyor actuating means manually operable for advancing the conveyor, means for placing the printer driving means into operation with each actuation of the conveyor actuating means, and brake means operable by the conveyor actuating means as it approaches the end of its conveyor advancing 40 stroke to prevent the conveyor from over-traveling.

4. In a postage printing machine, postage printing means, driving means operable for driving the printer means through a single operating 50 cycle each time said driving means is placed into operation, conveyor means for advancing mail matter through the printing means, pulley means for the conveyor, a ratchet wheel carried by the pulley, an oscillatory plate for the ratchet wheel, 55 pawl means carried by the plate and arranged to engage the teeth of the ratchet wheel for turning the pulley and thereby advancing the conveyor, manually operable means for oscillating the plate, means for limiting the oscillatory motion of the 60 plate for predetermining the amount of travel of the conveyor for each actuation of the plate, and means operatively associated with the oscillatory plate for placing the printer driving means into operation each time the plate approaches the 65 conveyor advancing end of its oscillatory stroke.

5. In a postage printing machine conveyor, a pair of spaced pulleys, a conveyor belt for the pulleys, a ratchet wheel carried by one of the pulleys, an oscillatory plate operatively mounted adjacent the ratchet wheel, pawl means carried by the plate and arranged to engage the teeth of the ratchet wheel for turning the pulley to thereby advance the conveyor belt, manually operable 70 means for oscillating the plate, and means for 75

limiting the oscillatory motion of the plate for predetermining the amount of travel through which the conveyor belt will be advanced for each actuation of the plate.

5 6. In a postage printing machine conveyor, a pair of spaced pulleys, a conveyor belt for the pulleys, a ratchet wheel carried by one of the pulleys, an oscillatory plate for the ratchet wheel, pawl means carried by the plate and arranged 10 to engage the teeth of the ratchet wheel for turning the ratchet wheel pulley to thereby advance the conveyor belt, manually operable means for oscillating the plate, means for limiting the oscillatory motion of the plate for predetermining 15 the amount of travel through which the conveyor belt will be advanced for each actuation of the plate, and means operable by the plate as it reaches the end of its active stroke for causing the postage printing means to operate through 20 one cycle of operation.

7. In a postage printing machine conveyor, a pair of spaced pulleys, a conveyor belt for the pulleys, a ratchet wheel carried by one of the pulleys, an oscillatory plate operatively mounted adjacent the ratchet wheel, a pawl means carried 25 by the plate and arranged to engage the teeth of the ratchet wheel for turning the ratchet wheel pulley to thereby advance the conveyor belt, manually operable means for oscillating the plate, 30 means for limiting the oscillatory motion of the plate for predetermining the amount of travel through which the conveyor belt will be advanced for each actuation of the plate, and spring means operable for returning the oscillatory plate to 35 its starting position after each actuation thereof.

8. In a postage printing machine conveyor, a pair of spaced pulleys, a conveyor belt for the pulleys, a ratchet wheel carried by one of the pulleys, an oscillatory plate for the ratchet wheel, 40 pawl means carried by the plate and arranged to engage the teeth of the ratchet wheel for turning the ratchet wheel pulley to thereby advance the conveyor belt, manually operable means for oscillating the plate, means for limiting the oscillatory motion of the plate for predetermining the amount of travel through which the conveyor belt will be advanced for each actuation of the plate, and a brake means operable by the plate as it reaches the end of its active stroke for stopping 45 the conveyor belt.

9. In a postage printing machine conveyor, a pair of spaced pulleys, a conveyor belt for the pulleys, a ratchet wheel carried by one of the pulleys, an oscillatory plate for the ratchet wheel, 50 pawl means carried by the plate and arranged to engage the teeth of the ratchet wheel for turning the ratchet wheel pulley to thereby advance the conveyor belt, manually operable means for oscillating the plate, means for limiting the oscillatory motion of the plate for predetermining the amount of travel through which the conveyor belt will be advanced for each actuation of the plate, and means for automatically disengaging the pawl means from the ratchet wheel when the oscillatory 55 plate is located at its starting position.

10. In a postage printing machine conveyor, a pair of spaced pulleys, a conveyor belt for the pulleys, a ratchet wheel carried by one of the pulleys, an oscillatory plate for the ratchet wheel, 60 pawl means carried by the plate and arranged to engage the teeth of said ratchet wheel for turning the ratchet wheel pulley to thereby advance the conveyor belt, manually operable means

for oscillating the plate, means for limiting the oscillatory motion of the plate for predetermining the amount of travel through which the conveyor belt will be advanced for each actuation of the plate, spring means operable for returning the oscillatory plate to its starting position after each actuation thereof, and means for automatically disengaging the pawl means from the ratchet wheel when the oscillatory plate is returned to its starting position.

11. In a postage printing machine, postage printing means, conveyor means for advancing mail matter through the printing means, a driving mechanism operatively connectible with either the conveyor or printer but not with both at the same time, manually operable conveyor advancing means, means for connecting the driving mechanism to the printer with each actuation of the manually operable conveyor advancing means, and a control means operable when actuated to one position for rendering inoperative the means for connecting the driving mechanism to the printer and for rendering the driving mechanism connectible to the conveyor means and operable when actuated to a second position for rendering operable the means for connecting the driving mechanism to the printer and for disconnecting the driving mechanism from the conveyor means.

12. In a postage printing machine, postage printing means, conveyor means for advancing mail matter through the printing means, a driving mechanism operatively connectible to either the conveyor or printer, manually operable conveyor advancing means for advancing the conveyor a predetermined distance with each actuation thereof, said manually operable conveyor advancing means being disconnectible from the conveyor while the conveyor is being operated by the driving mechanism, and means for connecting the driving mechanism to the printer each time the manually operable conveyor advancing means is actuated to advance the conveyor.

13. In a postage printing machine, postage printing means, conveyor means for advancing mail matter through the printing means, a driving mechanism operatively connectible to either the conveyor or printer, manually operable conveyor advancing means for advancing the conveyor a predetermined distance with each actuation thereof, said manually operable conveyor advancing means being disconnectible from the conveyor while the conveyor is being operated by the driving mechanism, means for connecting the driving mechanism to the printer each time the manually operable conveyor advancing means is actuated to advance the conveyor, and means operable for rendering the last named means inoperative while the conveyor means is connectible to the driving mechanism.

14. In a postage printing machine, postage printing means, conveyor means for advancing mail matter through the printing means, a driving mechanism operatively connectible to either the conveyor or printer, manually operable conveyor advancing means, means for connecting the driving mechanism to the printer each time the manually operable conveyor advancing means is actuated, and means operable for rendering the last named means inoperative while the conveyor is connectible to the driving mechanism.
